UNITED STATES PATENT OFFICE.

ADOLPH L. ALDAY, OF CLEVELAND, OHIO.

FLYING-MACHINE.

1,171,162.

Specification of Letters Patent. Patented Feb. 8, 1916.

Application filed April 30, 1915. Serial No. 25,044.

To all whom it may concern:

Be it known that I, ADOLPH L. ALDAY, a citizen of the United States, residing at Cleveland, in the county of Cuyahoga and State of Ohio, have invented new and useful Improvements in Flying-Machines, of which the following is a specification.

This invention relates to flying machines, and particularly to improvements in the construction of the planes or supporting surfaces for machines of this character, the primary object of the invention being to provide a novel construction and arrangement of planes whereby greater lifting power may be obtained, an efficient type of slow flying machine produced, and advantages gained in enabling the lifting power to be regulated as circumstances require to vary the flying speed and lifting capacity under different conditions of service.

A further object of the invention is to provide a flying machine embodying adjustable planes under the control of the aviator, which may be disposed at different working angles for slow or fast flight, for easy and rapid launching, and for braking and readily controlling the speed of descent.

A still further object of the invention is to provide a flying machine having adjustable wings which may be positively controlled for the purposes described, and which in addition are automatically controlled according to the density or pressure of the air, to compensate for variations in the density and pressure of the air to normally maintain a determined lifting or supporting capacity.

A still further object of the invention is to provide adjustable planes of the character described in connection with underlying fixed planes, whereby a substantially constant and uniform pressure of the air on the adjustable planes is secured.

The invention consists of the features of construction, combination and arrangement of parts herein fully described and claimed, reference being had to the accompanying drawing, in which:—

Figure 1 is a top plan view of a flying machine embodying my invention. Fig. 2 is

a similar view with the upper planes omitted. Fig. 3 is a sectional front elevation on the line 3—3 of Fig. 1. Fig. 4 is a side elevation of the machine. Fig. 5 is a fore-and-aft section on line 5—5 of Fig. 1. Fig. 6 is a fragmentary top plan view on an enlarged scale of the fuselage, showing the plane controlling device.

Referring to the drawings, 1 designates the body or fuselage of the machine, which may be in general of the monoplane, biplane or triplane type, and which body or fuselage includes a car or compartment 2 containing one or more seats for the accommodation of the aviator and a passenger, if any.

Extending from the sides of the body or fuselage are lower supporting rods or bars 3, arranged one in rear of the other, which rods or bars support the wings 4 of a lower plane. These wings 4 are rigidly mounted, and are preferably straight or flat, operating in practice as air deflecting and retaining surfaces, as hereinafter fully described.

Arranged above the wings 4 of the lower plane are the wings 5 of an upper supporting plane. These wings 5 are disposed at a proper elevation above the wings 4 and are curved in a fore-and-aft direction for the dynamical action of the air therein. As shown, the said wings 5 are pivotally mounted to tilt vertically on supporting bars or rods 6 connected with the front and intermediate bars or rods 3 by supporting and reinforcing brackets 7. The wings 5 are designed to have sufficient lifting capacity to support the weight of the machine and its load under all conditions of service.

Connected at intervals with the tail portion of each wing 5 are controlling cables 8 consisting of rear sections 8 passing over guide pulleys 9 supported by the rear rods or bars 3 and fastened at their upper rear ends to the wings 5, and front sections 9 passing forwardly and inwardly around guide pulleys 10 and connected with a main controlling cable 11, the said main controlling cables 11 of the respective series of cables connected with the respective wings 5 being extended into the sides of the car, 100

passed around front and rear guide pulleys 12 and 13 and thence connected with a controlling device 14. The sections 8 and 9 of each cable are united by a coiled contractile 5 spring 15, forming an elastic connection between them, whereby the wings 5 are adapted to be automatically and manually adjusted and controlled. The controlling device 14 preferably comprises a drum to 10 which the main cables are connected in such manner that both cables may be simultaneously drawn upon and taken up or released and let out.

From the foregoing description it will be 15 apparent that when the machine is in flight, air channels or passages 16 are formed between the superposed planes 4 and 5 and that the wings 4 keep the air compressed by the plane 5 from being deflected downwardly too rapidly by the curved surfaces 20 of the wings 5. As a result the body of compressed air will be constantly maintained in contact with wings 5, forming a compressed, cushioning strata on which the machine is supported and glides in flight. The springs 15 maintain a normally fixed 25 relationship between the wings 5 and wings 4, but should the normal volume of air in the channels 16 be augmented unduly, the pressure of the air on the trail ends of 30 the wings 5 will force the same upwardly, the wings tilting on the axes 6 and the springs 15 extending to permit such movement, whereby the excess air is allowed to escape. If, on the contrary, the normal 35 volume of air should decrease, the relief of pressure on the rear ends of the wings 5 will cause the springs 15 to draw the rear ends of said wings to a greater extent downwardly, thus allowing the contained air to 40 be more closely compacted to give the desired supporting effect and compensate for the temporary loss in volume of air. Provision is thus made for securing and maintaining a substantially constant or uniform 45 lifting action when the machine in flight traverses portions of the air varying in density, by which maximum stability and steadiness of flight are obtained. At the same time the springs 15 provide yielding 50 connections which permit the wings 5 to be manually adjusted by means of the controlling device, to regulate the distance between said wings and the wings 4, thus enabling the angle of incidence of the wings 5 to be varied for slow or fast flying and to 55 enable a maximum lifting effort to be secured to easy and rapid launching. The wings 5 may also be drawn downward to an increased angle of incidence to bank the air 60 against the wings 4 and regulate its passage through the channel 16, enabling the machine to be braked or its speed retarded at the will either in flight or in landing op-

erations, thus adapting the machine to be easily landed and controlled under all conditions of service.

From the foregoing description, taken in connection with the drawings, the construction, mode of operation and advantages 70 of my invention will be readily understood and appreciated by those versed in the art.

While the operations set forth assume the use of the lower wings 4, it will, of course, be understood that the majority of these operations to an appreciable extent may be secured without the use of such wings 4, and therefore I do not desire to be restricted to their use, except when directly specified in the appended claims. 80

I claim:—

1. A flying machine including a body, fixed wings upon the body, curved wings pivotally mounted on the body above said fixed wings to tilt vertically on horizontal 85 transverse axes, means connected with the rear portions of said curved wings for manually tilting the wings downwardly or permitting them to tilt upwardly under air pressure, and elastic elements in such connections for permitting the wings to have 90 automatic adjustment.

2. A flying machine including a body, fixed wings upon the body, a controlling device within the body, curved wings 95 mounted on the body above said fixed wings to tilt vertically on horizontal transverse axes, cables connecting the controlling device with the rear portions of the wings, and springs or like elastic connections in the 100 lengths of said cables.

3. A flying machine including a body, a controlling device therein, curved wings mounted to tilt on horizontal transverse axes, guide pulleys upon the body beneath 105 the front and rear portions of said wings, cables connected at their front and rear ends to the controlling device and rear edges of the wings and passing intermediately over said guide pulleys, and springs in the 110 lengths of said cables on lines between the sets of guide pulleys.

4. A flying machine including a body, stationary flat wings upon the body, curved wings upon the body above said fixed wings, 115 said curved wings being mounted to tilt vertically on horizontal transverse axes, and connections for adjusting said tiltable wings with relation to said fixed wings, said connections including elastic means in the 120 length thereof for permitting the curved wings to have automatic adjustment.

5. A flying machine including a body, fixed flat wings upon the sides of the body, curved supporting wings above said flat 125 wings, said curved wings being mounted to tilt vertically on horizontal transverse axes, a control device within the body, front and

rear guide pulleys beneath the curved wings, controlling cables connected at their opposite ends to the control device and rear edges of the curved wings, said cables passing centrally over said pulleys, and contractile springs in the lengths of the cables between the sets of pulleys.

In testimony whereof I affix my signature in presence of two witnesses.

ADOLPH L. ALDAY.
